UNITED STATES PATENT OFFICE.

JOSEPH WARREN COULSTON, OF PHILADELPHIA, PENNSYLVANIA.

SIGNAL-LIGHT FOR VESSELS.

SPECIFICATION forming part of Letters Patent No. 395,880, dated January 8, 1889.

Application filed October 1, 1888. Serial No. 286,852. (No model.)

To all whom it may concern:

Be it known that I, JOSEPH WARREN COULSTON, a citizen of the United States, and a resident of Philadelphia, Pennsylvania, have invented certain Improvements in Signal-Lights for Vessels, of which the following is a specification.

My invention consists of certain improvements in signal-lights for vessels, the invention being based upon that set forth in the patents granted to George T. Parry respectively on the 25th day of December, 1883, No. 290,918, and on the 13th day of October, 1885, No. 328,059; and the object of my present improvements is to provide a vessel with signal-lights so arranged as to warn and direct an approaching vessel more effectively than before. This object I attain by the use of a supplementary white light or lights visible only from dead astern and from a limited range to port or starboard of dead astern, in combination with the ordinary colored port or starboard lights or with said lights and the colored supplementary side or range lights forming the subject of said George T. Parry's patents above alluded to.

In the accompanying drawings, Figure 1 is a diagram illustrating one method of carrying out my invention; and Figs. 2 and 3 are diagrams of signal-lanterns, illustrating other and simpler ways of carrying out my invention.

The invention of the said George T. Parry consisted mainly in the use, in connection with the ordinary colored port and starboard lights, P and S, of a vessel, of supplementary colored port and starboard lights—such as in Fig. 1 are represented by the letters P' and S', respectively—these supplementary side lights being screened from observation from dead ahead or from a point or more on either the port or starboard bow, while the stern range of the supplementary side lights was generally the same as that of the ordinary side lights—that is to say, to a point or two abaft the beam—so that the relation of the supplementary colored port or starboard side light to the usual colored port or starboard light indicated the course of the vessel carrying the same to another vessel approaching it. These side lights, however, did not serve to warn or direct a vessel approaching

dead astern, or from a number of points to either port or starboard of dead astern up to one or two points abaft the beam, and with the view of overcoming this defect I provide 55 one or more white warning or object lights, which will serve to cover those points of the compass not hitherto lighted. For instance, the white warning-light may be visible from dead astern and from a number of points to 60 either port or starboard of dead astern, the forward range of said white warning or object lights extending, if desired, as far as the aft range of the colored side lights, so that the three sets of lights will serve to warn or 65 direct a vessel approaching from any point of the compass. Thus to a vessel approaching from dead ahead the usual colored port and starboard lights would be visible, while to a vessel approaching on either bow in a range 70 anywhere from a point or two from dead ahead to a point or two abaft the beam the usual colored side light and the first supplementary colored side light would be visible, the course of the vessel carrying the lights 75 being thus indicated to such approaching vessel and the course of the latter being governed accordingly, while to a vessel approaching from dead astern or from anywhere aft of the range of the colored side lights the white 80 warning or object signal would be visible, and the necessary change in the course of the approaching vessel would open up the colored side lights, and thus inform such approaching vessel of the position and course of the vessel 85 ahead.

In the diagram Fig. 1 I have shown one way of carrying out my invention in connection with lights arranged as in accordance with the Parry patents, the ordinary colored 90 port and starboard lights being in this case placed in the forward rigging, the supplementary colored side lights, P' S', in the main rigging, and the white object or warning lights P² S² in the mizzen rigging; but in order to dispense with the two extra lanterns and lantern-boxes which this would necessitate I prefer, in applying my invention to the Parry system, to provide one lantern-box with both the colored supplementary side light and 95 the white warning or object light, as shown in Fig. 2, so that one lantern will serve for 100

both, the lantern-casing being preferably provided with adjustable screens *a* and *b*, so that the aft range of the colored light P' or S' and the forward range of the white light P^2 or S^2 5 can be regulated as desired, for in some cases it may not be advisable to light all the points of the compass—that is to say, the forward range of the white warning or object lights P^2 or S^2 may not extend to the aft range of the 10 colored side lights, P' S' , so that there will be no likelihood of these two lights blending to view from a vessel approaching, say, from two points abaft the beam.

The white warning or object lights may be 15 used in connection with the ordinary colored side lights, if desired, when the use of the supplementary colored side lights is not considered necessary—an instance of a compound lantern for this purpose being shown in Fig. 20 3—and, if desired, a single white warning or object light at the stern may be used instead of having one on each side, said single light being properly shielded, so that its range will not cause blending or confusion of the white 25 warning or object light with the colored side lights.

Having thus described my invention, I claim and desire to secure by Letters Patent—

1. The combination, in signal-lights for vessels, of colored port and starboard lights, with a white warning or object light visible from dead astern and from a number of points to port or starboard of dead astern, but shielded from view from a point within the range of 35 the said port and starboard lights, all substantially as specified.

2. The combination, in signal-lights for vessels, of colored port and starboard lights, with white supplementary side lights constituting 40 warning or object lights visible from dead astern and from a number of points to port or

starboard of dead astern, but shielded from view from all points within the range of the colored port and starboard lights, all substantially as specified. 45

3. The combination, in signal-lights for vessels, of the usual colored port and starboard lights, colored supplementary side lights visible through a range including a number of points to port or starboard, respectively, and 50 one or more white warning or object lights visible from dead astern and through a range including a number of points to port and starboard of dead astern, but shielded from view from all points within the range of the colored port and starboard lights, all substantially as specified. 55

4. The within-described compound side light, consisting of a single lantern-box having a colored side light and a white warning or object light, the latter being visible from dead astern and from a number of points to port or starboard of dead astern, but shielded from view from all points in the range of the colored side lights, all substantially as specified. 60

5. The combination of the single lantern-box having a colored side light visible to port or starboard, and a white warning or object light visible from dead astern and from a number of points to port or starboard of dead astern, with adjustable shields for governing the range of said colored and object lights, all substantially as specified. 70

In testimony whereof I have signed my name 75 to this specification in the presence of two subscribing witnesses.

JOSEPH WARREN COULSTON.
